CAN CLOSURE

Charles R. Rau, Chattanooga, Tenn., assignor to
 Samuel Stamping and Enameling Company,
 Chattanooga, Tenn., a corporation of Tennessee

Application March 24, 1942, Serial No. 436,031

14 Claims. (Cl. 222—483)

This invention is a closure for containers, particularly for liquid containers.

The closure of the present invention is particularly adapted for liquids, such, for example, as oil or gasoline, although capable of general application. The container has a relatively large opening for filling and emptying purposes which is closed by a cover which is not hinged directly to the container, but is hinged to a hinge plate or link plate, which in turn is hinged to the container. Pivoted to the cover is a clamping member which has hooks which engage with studs on the container for holding the cover closed. The pressure of the clamping member is exerted on the cover through a resilient connection, a lost motion connection being provided to make up for wear of the parts, such, for example, as the wearing out of the usual gasket between the cover and the container. This resilient connection is preferably in the form of a spring at the center of the cover, the clamping member exerting a downward pressure on the spring to resiliently press the cover to closed position.

The cover is preferably provided with a dispensing spout in the form of a small pipe mounted therein, whereby small amounts of liquid may be dispensed if desired. The dispensing spout is provided with a threaded cap which may conveniently be carried by the hinge or link plate mentioned above, and this threaded cap is arranged to engage with the clamping member when the latter is in closed position, for holding the clamping member in such position. This threaded clamping means could take the form of a threaded stud instead of a threaded spout, but the threaded spout is preferred because of the dispensing ability thereof.

The principal features and objects of the invention are as follows:

1. A closure which is carried by a link plate, that is to say, a plate which is hinged both to the closure and to the container.
2. A closure wherein the cover has a clamping member pivoted thereto and which applies a resilient pressure to the cover.
3. To provide a clamping member which is pivoted to the cover with a lost motion connection and exerts a resilient pressure against the cover, the lost motion connection taking up wear in the parts.
4. To provide a closure having a dispensing spout therein.

5. To provide a closure having a dispensing spout therein and having a clamp pivoted thereto,

the cap for the dispensing spout serving also to lock the clamping member in closed position.

6. To provide a cover which has a clamping member having hooks or the like for engaging with suitable studs on the container for exerting a resilient pressure on the cover, the cover also having a dispensing spout which is closed by a closure cap which serves to lock the clamping member in closed position.

10. Further advantages of structure and operation will be described in connection with the accompanying drawing illustrating the present preferred embodiment of the invention, in which:

Fig. 1 is a perspective view of a container showing my improved closure;

Fig. 2 is a side view on an enlarged scale of the closure;

Fig. 3 is a section on the line 3—3 of Fig. 1; and

20. Fig. 4 is a section on the line 4—4 of Fig. 2.

Referring now to the drawing, 2 shows a metal container provided with a carrying handle 4. The container is provided with a neck 6. Seated on the upper edge of the neck 6 is a cover 8 provided with a peripheral flange 10 for holding a gasket 12.

30. In diametrically opposite positions on the cover 8 are bearings 14, through which bearings passes the long pivot pin or hinge pin 16 in suitable apertures 18. Apertures 18 are enlarged, to provide a lost motion connection, for a purpose to be explained.

35. Pivoted on the long pin 16 is a hinge or link plate 20, the link plate 20 being bent around the pin to provide a bearing therefor, as at 21. Plate 20 is in turn pivoted or hinged to the neck 6 by means of downwardly bent ears 22, through which ears is passed a hinge pin 24, this pin being carried in a suitable bearing 26 in the bracket 28 secured to the neck 6.

40. The clamping member for the cover 8 will now be described. This clamping member, indicated generally at 30, is of arcuate, U-shaped construction, and is provided at each end with a pair of downwardly bent ears 32 which straddle the bearings 14 on the cover 8. The hinge pin 16, already described, passes through these ears and provides a pivot for the clamp 30. The clamping member 30 is also provided with hook members 34 which engage under suitable studs 36 on the neck 6 for drawing the clamping member 32 downwardly and holding it in clamping position.

45. An important feature of the invention is that the clamp 30 exerts a resilient pressure on the cover 8 and this is effected by the pin 16 pressing

downwardly in bearing 21, as the hooks 34 draw the clamping member 30 downwardly. This downward pressure presses the bearing 21 downwardly against the inverted cup 38 in which is seated a spring 40, the other end of the spring being in a cup 42 positioned at the central part of the cover 8. Even though the gasket 12 should get thinner and thinner, as it would do in use, a substantially constant resilient pressure would always be exerted on the cover by the spring 40, due to the lost motion connection at 18 and the up and down movement of the cup 38 over the spring 40.

The cover 8 is preferably provided with a dispensing spout 42, the upper end of which is threaded and provided with a threaded closure cap 44, which cap is provided with a groove 46 and lower flange 48, to form a swivel connection for the wire member 50 which passes around the cap and then passes through the collar 52, the wire here being doubled. The doubled wire is pivoted to the hinge plate 20 as by providing the hinge plate with up-struck perforated lugs or arches 54, through which is passed a hinge or cotter-pin 56, the wire 50 being formed into an eye 58 encircling the pin 56.

In operation, and as shown in Fig. 3, the closure is entirely closed, the outer part of the flange 48 of the cap 44 engaging over the inner edge of the clamping member 30, thereby locking the clamping member in clamping position. In order to dispense a small amount of liquid, the cap 44 is removed from the spout 42 and the liquid poured out through the spout. To facilitate the entrance of air into the can for such dispensing, a conventional air inlet device 60 provided with a threaded cap, is used.

In order to remove the cover 8 entirely, the cap 44 is removed and the fingers inserted under the flange 62 of the clamping member; the clamping member is swung clockwise about 90°, thereby releasing the hooks 34 from the studs 36; further lifting of member 30 serves to remove the cover 8 entirely. In order to close the container, the parts are swung counterclockwise until the clamping member is in the position of Fig. 1, after which the closure cap 44 is screwed down, thereby locking the clamping member in clamping position.

While the invention has been described in some detail, it should be understood that the invention is not to be limited to the precise details herein described, but may be carried out in other ways.

I claim as my invention:

1. A closure for a container, comprising a hinge plate, means pivotally connecting one end of said hinge plate to the container, a cover, means pivotally connecting the other end of said hinge plate to the cover end of the hinge plate, and engageable with the container, for securing the cover in closed position.

2. A closure for a container, comprising a hinge plate, means pivotally connecting one end of said hinge plate to the container, a cover, means pivotally connecting the other end of said hinge plate to the cover, studs on the container, and a clamping member, pivoted to said cover, and to the hinge plate, having hooks engageable with said studs, for securing the cover in closed position.

3. A closure for a container, comprising a hinge plate, means connecting one end of said hinge plate to the container, studs on the container, a clamping member having hooks en-

gageable with said studs, a cover, and coaxial means for pivotally connecting the hinge plate and the clamping member to the cover.

4. A closure for a container, comprising a hinge plate, means for pivotally connecting one end of the hinge plate to the container, a clamping member, a cover, means for pivotally connecting the clamping member, and the other end of said hinge plate, to the cover, said last mentioned means including a resilient member for exerting spring pressure on the cover for holding it closed.

5. A closure for a container, comprising a hinge plate hinged to the container, a cover, a clamping member, means comprising a common hinge pin, for pivotally connecting the clamping member to the cover and for pivotally connecting the cover to the hinge plate, and means, carried by the clamping member and engageable with the container, for holding the clamping member in clamping position.

6. A closure for a container comprising a cover, a hinge plate pivoted at its opposite ends respectively to the cover and to the container, said hinge plate being permanently attached both to the container and to the cover, by its pivotal connections therewith in both the open and closed positions of the cover, a clamping member pivoted to the cover and engageable with the container, for holding the cover closed, and means including a threaded member carried by the cover, for holding the clamping member in clamping position.

7. A closure for a container comprising a cover, a hinge plate pivoted respectively to the cover and to the container, a clamping member pivoted to the cover and engageable with the container, for holding the cover closed, a threaded member carried by the cover, and a cooperating threaded cap pivotally carried by said hinge plate, for holding the clamping plate in clamping position.

8. A closure for a container comprising a cover, a spout carried thereby, means for hinging the cover to the container, a clamp pivoted to the cover and engageable with the container, for holding the cover closed, and a cap for closing said spout, said cap also being engageable with the clamping member, for locking it in clamping position.

9. A closure for a container comprising a cover, a spout carried thereby, a link plate hinged, respectively, to the container and to the cover, a clamping member, hinged to the cover and engageable with the container for holding the cover closed, and a closure cap for said spout, carried by said hinge plate.

10. A closure for a container comprising a cover, a spout carried thereby, a link plate hinged, respectively, to the container and to the cover, a clamping member, hinged to the cover and engageable with the container for holding the cover closed, and a closure cap for said spout, pivotally mounted on said hinge plate, said cap, when applied to the spout, engaging also with the clamping member, for locking it in closed position.

11. A closure for a container, comprising a cover, a hinge plate pivoted to the container on a horizontal axis alongside the cover, said plate being also pivoted to the cover and extending over the top thereof and being substantially parallel therewith when the cover is closed, and a clamp pivotally carried by said cover coaxially with the pivotal connection of the hinge plate

and cover, and engageable with the container, for holding the closure in closed position.

12. A closure for a container, comprising a cover, a hinge plate, pivoted at its opposite ends to the container and to the cover, respectively, a clamp, also pivoted to one end of said hinge plate, studs carried by the container, hooks carried by the clamp, engageable with said studs, and spring means, cooperating with the clamp and cover, for exerting resilient pressure on the cover when the clamp is turned into engagement with said studs to clamping position.

13. A closure for a container, comprising a cover, a hinge plate, pivoted at its opposite ends to the container and to the cover, respectively, a clamp, also pivoted to one end of said hinge plate and connected to the cover by a lost motion connection, studs carried by the container, hooks carried by the clamp, engageable with said

studs, and spring means, cooperating with the clamp and cover, for exerting resilient pressure on the cover when the clamp is turned into engagement with said studs to clamping position.

14. A closure for a container, comprising a cover, a hinge plate, pivoted at its opposite ends to the container and to the cover, respectively, a clamp, also pivoted to one end of said hinge plate, studs carried by the container, hooks carried by the clamp, engageable with said studs, spring means, cooperating with the clamp and cover for exerting resilient pressure on the cover when the clamp is turned into engagement with said studs to clamping position and locking means carried by the cover and engageable with the clamp when closed, for holding the clamp in locking position.
